UNITED STATES PATENT OFFICE.

REINHOLD LEWITZ, OF NEW YORK, N. Y.

FLYING-MACHINE.

No. 856,073.

Specification of Letters Patent.

Patented June 4, 1907.

Application filed June 13, 1906. Serial No. 321,428.

To all whom it may concern:

Be it known that I, REINHOLD LEWITZ, a citizen of the Empire of Germany, residing in New York, in the borough of Manhattan, county and State of New York, have invented certain new and useful Improvements in Flying-Machines, of which the following is a specification.

This invention relates to an improved flying machine which is raised and lowered in the air and propelled and steered in the same by motor power without a balloon-field. The lifting, lowering, driving, steering and balancing in the air in relation to the longitudinal transverse axis is accomplished by two motors which are located symmetrically to the vertical central axis and in line with the longitudinal axis of the flying machine.

The invention consists of a flying machine which comprises a supporting-frame having braced front and rear ends, motors supported by said frame in line with the longitudinal axis of the same, a pair of lowering and lifting wheels supported on independent shafts, one within the other, and driven in opposite direction to each other, two sets of balancing-wheels below said lifting and lowering wheels, the wheels of each pair being moved in opposite direction to each other, a pair of forwardly or backwardly-driving wheels which likewise are applied to independent shafts to which rotary motion in opposite direction is imparted, said driving-wheels being located at the front end of the supporting-frame, and a steering-wheel at the rear end of the supporting-frame, and vertical wings located at opposite sides of the supporting-frame and adapted to impart, in connection with the rear wheel or propeller, a steering action to the structure.

The invention consists further in the novel construction of the different lifting and lowering wheels, balancing-wheels, driving wheels and steering-wheel, and in certain additional details of construction which will be fully described hereinafter and finally pointed out in the claims.

In the accompanying drawings, Figure 1 represents a side-elevation of my improved flying machine, Fig. 2 is a plan-view of the same, partly in section, the lifting and lowering wheels and balancing-wheels being indicated in dotted lines, Fig. 3 is a rear-elevation of the flying machine, Fig. 4 is a plan-view of the lifting and lowering wheels, showing one form of construction of the same,

Fig. 5 is a side-view of Fig. 4, and Fig. 6 is a vertical central section on line 6, 6, Fig. 4.

Similar letters of reference indicate corresponding parts in the different figures of the drawings.

Referring to the drawings, *a* represents the supporting-frame of my improved flying machine. This frame is made of oblong side, base and top tubes, preferably of aluminium, thin steel or other light yet strong material. The oblong supporting-frame *a* is properly braced so as to have the required degree of stiffness and strength, the bottom frame being provided with a platform on which two motors *m*, *m*¹, one located in the front and the other in the rear of the vertical axis of the machine and equidistantly therefrom so as to be properly balanced, are supported. Any suitable construction of gasoline or other motor may be used, provided the same possesses the required strength and lightness. In the center, between the motors *m*, *m*¹, is arranged a suitable railing *b* forming an enclosure for passengers, while the motormen are placed near the motors in any suitable manner.

The supporting-frame is provided with a forwardly-extending brace-frame *a*¹ and with a rearwardly-extending brace-frame *a*², the front frame *a*¹ supporting in suitable bearings a horizontal forwardly-extending tubular shaft *s*, and in the shaft *s* is arranged a second shaft *s*¹, which latter is longer than the tubular shaft so as to extend beyond the same, each shaft *s*, *s*¹ carrying a driving-wheel *d*, *d*¹, which wheels are rotated by suitable power transmission from the front motor in opposite direction to each other so as to produce a driving action on the flying machine either in forward direction or in backward direction, according to the direction of motion of the two driving-wheels *d*, *d*¹. The rear brace-frame *a*² supports a vertical steering-wheel *e*, the shaft of which is supported transversely in bearings of the brace-frame *a*², said steering-wheel receiving rotary motion from the rear motor *m*¹ or any suitable power-transmitting mechanism from the same. The supporting-frame *a* is provided with a number of cushion-springs *t* at the bottom part, so as to permit the lowering to and resting on the ground of the flying machine.

In central step-and-neck bearings of the supporting-frame *a* is supported an upright tubular shaft *s*², within which is arranged a

second shaft s^3 that turns through the tubular shaft s^2 , said shafts carrying, at some distance above the top of the supporting-frame a , two lifting and lowering wheels f, f^1 of much greater diameter than the driving-wheels d, d^1 or the steering-wheel e , said lifting and lowering wheels being rotated in an opposite direction so as to balance each other. They rotate in one direction for the purpose of lifting the entire structure, and in the opposite direction for permitting the lowering of the flying machine. Below the lifting and lowering wheels f, f^1 and immediately above the top of the supporting-frame a , are arranged four rotary wheels g , to which I have given the name of "balancing-wheels," which are applied to vertical shafts g^1 that turn in neck-bearings of the supporting-frame near the corners thereof, all of them being of equal diameter, and smaller in size than the lifting and lowering wheels, the pair of front balancing-wheels rotating in opposite direction to each other and the pair of rear wheels also rotating in opposite direction to each other and to the front wheels, as clearly indicated by the arrows in Fig. 2. Motion is imparted to the two pairs of balancing-wheels by the motors m, m^1 , the front wheels receiving motion from the motor m and the rear wheels receiving motion from the motor m^1 by means of suitable chain-and-sprocket-wheel transmissions, which are indicated diagrammatically in Fig. 2. All the vertical shafts of the lifting and lowering wheels and balancing-wheels are provided with antifriction roller bearings so as to reduce the friction as much as possible.

At opposite sides of the supporting-frame a and centrally to the side-frames of the same, are pivoted in suitable bearings two wings w , which are capable of motion in forward or backward direction, as indicated by the arrows in Fig. 2, and which are adjusted simultaneously at an angle of 90° to the side-frames, or at a lesser angle, according as the machine is to be driven to the right or left-hand side, the position of the wings holding the machine before the wind, in connection with the steering action of the hind propeller, according as the same is turned in one or the opposite direction.

The lifting and lowering wheels, and the balancing-wheels, are preferably made of the construction shown in Figs. 4 to 6, in which a central group u of vertical tubes is arranged around a shaft, a second group v , concentric to the inner group, of slightly inclined tubes, and a third group y of still more inclined tubes, which gradually decrease in size from the inner toward the outer circumference of the group, and which overlap each other at the ends, as shown clearly in Figs. 4 to 6.

The tubes forming the wheels are made of thin waterproofed or parchmentized paper, or canvas-covered tubes, or aluminium tubes, so

that the required degree of lightness is obtained. As the different groups of tubes forming the wheels are rapidly moved through the air, the air is forced through all the inclined tubes, whereby the lifting action is imparted when the two pairs of wheels f, f^1 are turned in one direction toward each other, or the lowering action imparted when the same are turned in opposite direction to the former motion. The group u of vertical tubes is used merely for supporting the inclined tubes. The construction of these wheels is based on the same principle, a pair of each being arranged with the exception of the steering-wheel, which is a single wheel. The arrangement in pairs of the lifting and lowering, driving and balancing wheels, is for the purpose of equalizing the effect of the same on the supporting-frame of the machine. Each of the driving and steering wheels is constructed of a single group of inclined tubes arranged as shown in Fig. 1.

Any approved power-transmitting mechanism between the motors and the shafts of the different wheels is employed for imparting the different motions required. The steering-wings are operated by a suitable lever mechanism by the man attending the rear motor, who also has charge of the direction of motion in which the steering-wheel e is to be rotated. By permitting the steering-wheel to rotate in one or the opposite direction and setting simultaneously the steering-wings in one or the opposite direction to the vertical transverse axis of the flying machine, the steering of the same toward the right or the left hand is produced, while the motion in forward or backward direction is obtained by the driving-wheels d, d^1 , and the lifting and lowering of the structure by the pairs of lifting and lowering wheels f, f^1 and the two pairs of balancing-wheels g .

By the coöperation of the different rotating wheels, the required motions are imparted to the flying machine and its steady position in the air obtained, while the steering takes place by the rear wheel in connection with the steering-wings at the sides of the supporting-frame.

My improved flying machine combines great lightness with strength as the material employed in making the supporting-frame, wheels and wings is of the greatest possible lightness consistent with strength. By waterproofing the different wheels, the flying machine can be used while it rains as the rain has no effect on the same. Owing to the speed imparted to the different sets of wheels, the flying machine can be raised or lowered, moved forward or backward, or steered to one side or the other, it being within the control of the motorman, and built of the proper size, as calculated by the weight of the machine, its motors and accessories. Ascensions can be made regardless of the tempera-

ture of the air and the direction and velocity of the wind, the machine being propelled with greater ease in a direction opposite the direction of the wind than with the same, and 5 guaranteeing by the almost entire substitution of rotary motion in all the driving-wheels and the avoidance of reciprocating motion, that approach to a motor-driven flying machine which has been sought after for some 10 time, and is still sought after, by the inventors devoted to this class of machines.

Having thus described my invention, I claim as new and desire to secure by Letters Patent:

15 1. A flying machine consisting of a supporting-frame with tapering front and rear brace-frames, two large-sized lifting and lowering wheels above the supporting-frame rotating in opposite direction to each other, 20 two pairs of balancing-wheels, the wheels of each pair rotating in opposite direction to each other, a pair of front driving-wheels rotating in opposite direction to each other, a rear steering-wheel, motors on the supporting frame, and motion-transmitting mechanism 25 between the motors and the shafts of the different wheels.

2. A flying machine consisting of a supporting-frame with tapering front and rear brace-frames, two large-sized lifting and low-

ering wheels above the supporting-frame rotating in opposite direction to each other, two pairs of balancing-wheels, the wheels of each pair rotating in opposite direction to each other, a pair of front driving-wheels rotating 35 in opposite direction to each other, a rear steering-wheel, motors on the supporting-frame, motion-transmitting mechanism between the motors and the shafts of the different wheels, steering-wings attached to opposite sides of the supporting-frame, and means for setting the same at suitable angles to the transverse center-plane of the machine in connection with the motion of the steering-wheel. 40

3. In a flying machine, a wheel constructed of a number of groups of air-cutting tubes, an inner central vertical group, an intermediate inclined set of tubes, and a set of circumferential nearly horizontal tubes arranged with overlapping ends around the intermediate group. 50

In testimony, that I claim the foregoing as my invention, I have signed my name in presence of two subscribing witnesses.

REINHOLD LEWITZ.
